UNITED STATES PATENT OFFICE.

JOEL U. ADAMS, OF CINCINNATI, OHIO.

STEEL FOR CORSETS OR BELTS.

Application filed September 8, 1921. Serial No. 499,134.

To all whom it may concern:

Be it known that I, JOEL U. ADAMS, a citizen of the United States, residing at Cincinnati, in the county of Hamilton and 5 State of Ohio, have invented a new and useful Steel for Corsets or Belts, of which the following is a specification.

The object of this invention is to provide novel means for fastening the stays in the 10 casing of an abdominal belt or corset in such a way that they can not slip endwise and protrude through the casing at either end.

With the above and other objects in view, which will appear as the description proceeds, the invention resides in the combination and arrangement of parts and in the 15 details of construction hereinafter described and claimed, it being understood that, within the scope of what is claimed, changes in 20 the precise embodiment of the invention shown can be made without departing from the spirit of the invention.

In the drawings:—Figure 1 shows in front elevation, a device constructed in accordance with the invention, parts being 25 broken away; Figure 2 is a plan showing the reinforcing element; Figure 3 is a section on the line 3—3 of Figure 1; Figure 4 is a section on the line 4—4 of Figure 1.

30 The numeral 1 marks a reinforcing element, ordinarily in the form of a resilient strip and made at present, as a general thing, of steel. The reinforcing element is provided in its opposite edges with seats 2 disposed out of alinement with each other. The reinforcing element 1 may have the usual caps 3 on its ends. Flexible elements 4, such as pieces of tape are wound about the reinforcing element 1 and engage in the 35 seats 2, the ends 5 of the flexible elements extending in opposite directions. The numeral 6 denotes a covering which may be of cloth, leather or any other suitable material, the edges 7 of the covering being turned 40 inwardly, so that the covering is of double thickness. The covering 6 is placed in the reinforcing element 1, the ends 8 of the covering being folded to extend behind the reinforcing element and to cover the ends 45 of the reinforcing element. The reinforcing element and the covering 6 are placed against the body 9 of a corset, abdominal belt or the like, the covering being con-

nected to the body 9 by lines of side stitching shown at 10. This stitching, indicated 55 at 10, engages the oppositely extended ends 5 of the flexible elements 4 and attaches them to the body 9. Lines of end stitching 11 connect the extremities of the covering 6 with the body 9. 60

The construction of the device is such that the reinforcing element 1 will be held securely on the body 9, it being possible for the reinforcing element to bend with the body 9, but it being practically impossible 65 for the reinforcing element to shift its position appreciably, or to work its way through the body 9 or the covering 6.

It will be understood that after the device has been completed as shown in Figure 1, 70 the ends 5 of the flexible element 4 may be clipped off close to the longitudinal edges of the covering 6.

The stitching at 10 constitutes a single means for securing both the covering 6 and 75 the ends 5 of the flexible elements 4 to the body 9 along the longitudinal edges of the reinforcing element 1.

What is claimed is:—

1. In a device of the class described, a reinforcing element; a flexible member wound about the reinforcing element and having oppositely extended ends; a body; a covering for the reinforcing element; and a single means for securing both the covering and 80 the ends of the flexible member to the body along the longitudinal edges of the reinforcing element.

2. In a device of the class described, a reinforcing element having notches located out 90 of alinement with each other; a flexible member wound about the reinforcing element and engaged in the notches, the flexible member having oppositely projecting ends; a body; a covering for the reinforcing 95 element; and means for securing the covering and the ends of the flexible member to the body.

In testimony that I claim the foregoing as my own, I have hereto affixed my signature in the presence of two witnesses.

JOEL U. ADAMS.
